Application October 25, 1939, Serial No. 301,134

16 Claims. (Cl. 122—17)

Our invention relates to water heaters and means for controlling flow of air thereto for combustion purposes, and it has to do particularly with water heaters of the intermittent firing type that embody a storage tank, a main burner of the so-called "on" and "off" type located in a combustion chamber, and a flue which extends from the combustion chamber lengthwise of and in heat transfer relation to the storage tank.

Conventional devices of the foregoing character usually include temperature controlling means adapted to shut off the gas to the main burner when the temperature of the water in the tank is raised to a predetermined point and to cut in the burner when the temperature of the water drops below that point, the burner being equipped with a small, constant-burning pilot burner for igniting the fuel (gas, for example) in the main burner when the latter is turned on by the temperature controlling means. Also, the combustion chamber of such heaters is located at the bottom below the storage tank, and it is fully open at that point directly to atmosphere for supplying air for combustion of the burner gases. In the operation of such structure, there is a certain loss of heat from the water, particularly during "off" periods of the burner. This loss is due mainly to air passing directly and in an uncontrolled manner to the combustion chamber and thence into and through the flue, the amount of air naturally being in excess of that required to support combustion in the pilot burner. The flue is formed of a heat conducting metallic material and, since the water in the tank is in contact with at least one wall of the flue and this water is hotter than the air passing through the flue during the "off" period of the burner, there is a direct transfer of heat from the water in the tank to the flue contents, which results in a considerable loss of heat from the water. These conditions are induced in part by the small pilot burner flame which burns at all times, in that it is sufficient to heat the air in the combustion chamber to a point where its density, compared to that of the air externally of the heater, is such as to induce an upward flow of air through the flue. Also, the amount of heat loss from this cause is proportionate to the amount (including excess) passing through the flue during the "off" periods, and any material reduction in air flow will result in an increased over-all heater efficiency.

In some heaters of the foregoing character, flue means are employed which serve to more efficiently effect a transfer of heat from the flue

gases to the water, such, for example, as disclosed in United States Letters Patent No. 1,947,606, dated February 20, 1934; but, for the same reasons, such structures, when excess air, as above stated, is passed through the flue, as during the "off" burner periods, serve to transfer a greater amount of heat from the water to the upwardly moving air with resultant greater heat loss.

In some instances, it has been proposed to 10 overcome such loss by the use of automatic dampers, and the like, adapted to open when the main burner is "on," and to either shut off air entering the combustion chamber or close the exit of the flue when the burner is "off." Such devices, while 15 efficient in some respects, are objectionable because, in case of failure of the same to open at the proper time, incomplete combustion and explosions may occur.

One of the objects of our invention is to provide 20 an improved heater of the foregoing character which is of simple and inexpensive construction, is highly efficient in operation, and which includes new and novel means for reducing heat loss by limiting the flow of air to the combustion chamber and through the flue during the "off" 25 periods of the main burner to substantially the minimum amount of air required for operation of the pilot burner.

Another object is to provide a heater having a 30 flue with means for accomplishing a highly effective transfer of heat units from the flue contents to water in the tank and which, at the same time, is provided with air control means of such character that loss of heat from the water by the 35 tendency of the flue means to reverse the heat transfer from the water to the flue contents during "off" periods of the main burner is minimized, thereby increasing the thermal and service efficiency of the heater.

40 A further object is to provide a novel means for supplying secondary air for combustion purposes, the arrangement being such that the amount of air admitted to the combustion chamber and, in turn, passed through the flue is controlled by the combustion requirements of the 45 burner and is limited to substantially that amount required for combustion, whereby a greater utilization of the heat units discharged by the burner is experienced and the water in the storage tank is heated more quickly and is maintained in a desired heated condition for longer periods of time with less fuel consumption.

50 Still another object is to provide siphonic means of the foregoing character so constructed and arranged that, as the burner requirements

are reduced, the air passing through the flue is reduced and, as the burner requirements are increased, the flow of air through the flue is increased. To this end, we, preferably, provide an inverted siphon-type or U-shaped passage through which all air for combustion purposes must pass under the siphonic control of flue gases discharged from the flue. This U-shaped passage includes a so-called cold leg or air shaft open at one end to the atmosphere and connected at its other end to the combustion chamber and a so-called hot leg or flue leading from the combustion chamber, the air shaft being of such size and capacity relative to the flue that it creates a drag condition for controlling the flow of air therethrough.

Additional objects are to provide trap means for supplying air to a combustion chamber and by which heat loss through such air is minimized; to provide a heater so constructed and arranged that all operating parts are completely enclosed, providing a compact structure of improved appearance; to provide a heater of the foregoing character wherein the fuel control devices are located in the air shaft leading to the combustion chamber, so that they are swept by incoming secondary air and are maintained in a comparatively cool condition; to provide an improved form of heater casing that may be located in close proximity to a floor surface without danger of overheating; and to provide an air control for an intermittent firing type of water heater which includes a passage having connected hot and cold legs, the hot leg being constructed and arranged to minimize the excess air admitted during the "on" periods of the burner and the cold leg being constructed and arranged to minimize the excess air admitted during the "off" periods of the burner.

Other objects and advantages will become obvious as this description progresses and by reference to the drawings wherein—

Figure 1 is a vertical sectional view, partially in elevation, of one form of heater structure embodying our invention;

Fig. 2 is a section taken substantially on line 2—2 of Fig. 1;

Fig. 3 is a sectional view taken substantially on line 3—3 of Fig. 1;

Fig. 4 is a vertical sectional view, partially in section, of another form of water heater embodying our invention; and

Fig. 5 is a vertical sectional view of still another form of water heater structure embodying our invention.

Referring particularly to the structure shown in Figs. 1 to 3, inclusive, it includes a cylindrical tank 10 surrounded, in spaced relation, by a cylindrical shell 11, the space between the tank and shell being filled with an insulating material 12. The side walls of the tank 10 and shell 11 are extended downwardly as at 10^a and 11^a, respectively, beneath the bottom 10^b of the tank to form, in part, a comparatively shallow combustion chamber 13. The tank 10 and shell 11 are supported by a cylindrical, imperforate pan-like bottom member 14 upon which the lower edges of the tank and shell side walls seat. The bottom member 14 is supported upon legs 15 which space the heater as a whole from the supporting floor surface. The combustion chamber 13 is provided with a bottom in the form of a pan or plate-like member 16 supported above and in spaced relation to the bottom member 14 and forming with the latter an air space, the plate

member 16 having an opening 17 located near its central portion leading into the combustion chamber 13. It will be seen that, with this arrangement, the only inlet of air to the combustion chamber is through the opening 17 and the space 17^a therebeneath, which space is closed off from the atmosphere except through an air shaft, which will be described later. The storage tank 10 is provided with the usual cold water inlet 18 and hot water service outlet 19.

The heater structure is further provided with a cylindrical flue structure 20 extending vertically or lengthwise through the interior of the tank 10 so that it is surrounded by the water in the latter. The flue 20 is so arranged that its lower end terminates in the bottom 10^b of the tank, where it is connected directly to the combustion chamber 13, while its upper end terminates in the top of the tank 10, where it is connected by an additional flue connection 21 passing through the outer shell 11 and a draft diverter 22 to a discharge stack (not shown). With this arrangement, heat from the hot gases of combustion passing outwardly through the flue 20 are transferred to the water in the tank surrounding the flue. In the particular arrangement illustrated (Fig. 1), the transfer of heat from the flue products is amplified and improved by employing an additional heat transfer shell 24 extending into the flueway and bonded thereto for heat transfer purposes, as well as for the better distribution of the heated gases in the flue, all as more particularly and fully set forth in United States Letters Patent No. 1,947,606, granted to Bastian-Morley Company on February 20, 1934. In this arrangement, an efficient heat transfer is provided for without undue restriction to flow of the gases through the flue, but sufficient restriction is offered to minimize excess air in the flue products when the burner is in its "on" position and the heating of the water is in progress.

We have illustrated our invention, in Figs. 1 to 3, inclusive, as used in connection with a heater having a burner 25 supported upon the plate member 16 forming the bottom of the combustion chamber 13. Although the burner shown is adapted for gas as a fuel, it is to be understood that any other desired fuel and burner construction may be employed with good results. The burner 25 is, preferably, but not necessarily, of the type disclosed in United States Letters Patent No. 1,753,962, granted to Bastian-Morley company on April 8, 1930, and it includes a manifold 26, a plurality of upstanding burner nozzles 27 and a pilot burner 28. Gas is furnished to the main burner manifold through suitable piping 29 having therein a valve mechanism 30 controlled by a thermostatic element 31 located within the water in the tank 10. The arrangement, which is well known, is such that gas is cut into the burner through pipe 29 when the temperature of the water in the tank is reduced below a certain point and gas is cut off from the burner when the water in the tank reaches a predetermined temperature. The valve mechanism 30 is further controlled by the pilot burner 28 in such a way that so long as the pilot burner is lighted so as to ignite gas admitted through the pipe 29 to the main burner, the valve mechanism 30 will permit the flow of gas when the thermostat 31 functions to open the main gas valve, but if, for any reason the pilot flame should be extinguished so that gas admitted to the main burner would not be ignited, the pilot control functions to close the main valve mechanism 30 and prevent the flow of

gas to the main burner. The pilot control is of the thermoelectric type and it may include (Figs. 1 and 3) a thermocouple element 32 (Fig. 3) and a magnetic valve-operating unit 33 (Fig. 1) with proper electric connections including the pilot line 34 and other connections (not shown) enclosed therein; the arrangement being such that, so long as the thermocouple element 32 is heated by the pilot flame, the magnetic unit 33 is energized sufficiently to hold its valve (not shown) of the valve mechanism 30 open and permit the flow of gas, but in the event that the thermocouple element 32 should become cooled by extinguishing the pilot flame, the magnetic unit would become deenergized, permitting its gas flow control valve to close. In that event, no gas, regardless of the position of the valve controlled by the thermostatic element 31, could flow to the burner. Since this control mechanism may take any desired and well-known form, it will readily be understood by those skilled in the art and we do not believe it necessary to go further into details in showing and describing the same.

In carrying out our invention, we control the flow of secondary air to the combustion chamber 13 in such a way that only substantially that amount of air required for combustion is admitted, whereby, during the "off" periods of the burner, a minimum amount of secondary air is admitted thereby limiting the amount of air passing through the flue to the minimum. It will be seen from the foregoing description that burner 25 is arranged for intermittent firing thereby providing so-called "burner on" and "burner off" periods. The thermostatic control for the main burner is, preferably, of the so-called snap-action type, so that the burner is turned off and on practically instantaneously, the arrangement being such that the burner is either "on" full or is "off" entirely. By thus limiting the amount of air admitted, as well as that which must eventually exit through the flue 20, we reduce heat loss through the flue products to a material extent during the "off" periods of the burner. The foregoing air-limiting control feature is important in the use of any arrangement wherein heat from the products of combustion are passed through or along a wall surface separating the flue products from the water in the tank; and it is especially important in the use of a flue structure of the character above described, since the heat transfer ability of such flue structure is reversed when excess cold air is passed through the flue, with the result that heat is rapidly extracted from the water in the tank surrounding the flue. This condition, if permitted to exist, would cause a material efficiency-lowering heat loss.

In controlling the air admitted to the heater as above mentioned, we employ an inverted siphon or U-shaped passage means. One leg (the so-called cold leg) of this passage takes the form of a cold air inlet passage or shaft 35, and the other leg (the so-called hot leg) takes the form of the flue passage 20^a, the two legs being joined together to complete the U-shape by the combustion chamber 13 and the space 17^a therebeneath. Substantially all of the air admitted to the combustion chamber 13, for combustion purposes or otherwise, must pass through the cold leg of this U-shaped passage.

Specifically, the air shaft 35 takes the form of a tubular member 36, preferably of oblong, cross-sectional shape, and it is disposed substantially parallel with the flueway 20^a between the side

walls of the tank 10 and shell 11. The member 36 is of such length that its upper end terminates substantially in the top wall 11^a of the outer shell 11, and its lower end terminates substantially at the bottom plate member 16 where it connects with an elbow-shaped conduit member 37 connecting the vertical shaft laterally with the space 17^a leading to the combustion chamber 13. The upper or outer end of the shaft 35 is covered by a shell-carried hood 38 which is wide enough to extend over the top of the upper end of the shaft, and laterally thereof beyond the outer shell 11 to provide an air inlet 39 located laterally of the shaft 35 and at such a position that the air flows upwardly, then laterally and downwardly into the air shaft.

Although the combustion chamber 13 is normally connected with the atmosphere only through the shaft 35, it may be desirable, at times, to have access to the burner for repair and other purposes. To this end, we provide adjacent the combustion chamber a doorway 40 leading through the sections 11^a and 10^a of the outer shell and tank walls. The doorway, which is preferably of rectangular shape, is formed by a rectangularly shaped casing member 41 in which is received a rectangularly shaped door 42 curved to the contour of the outer shell. The door 42 is of the friction-fit type and it includes a metallic section 42^a and an inner insulating section 42^b and, with the door in place, its inner or insulating section is adapted to seat firmly against a flange 43 extending at substantially right angles from and around the door casing 41 (Fig. 3) at a point intermediate the inner and outer edges of the doorway. The door is held in place within the opening by a hinge-like unit 44 at one side and a rotatable latch unit 45 at its other side. The hinge unit member 44 includes one or more pins 46 engaging suitably provided openings in the adjacent part of the casing member 41. The latch 45 may include a rotatable latch element 47 carried by a rotatably mounted handle 48, the latch being adapted to enter a suitably provided slot in the adjacent part of the door casing 41. To place the door in position, the pins or prongs 46 are first inserted in their openings and the door then rocked inwardly and pressed into tight seating engagement with the flange 43, after which the handle 48 is turned to move the latch 47 to its latching position. When this is done, the doorway is sealed substantially airtight, but it may readily be removed by releasing the latch structure.

In the use of the structure above described, assuming that the main burner 25 is "on," the heated gases discharged from the burner pass upwardly into and through the flueway 20^a. The flue products are heated sufficiently to lower their density to the point where an updraft is created in the flueway 20^a, causing sufficient air to be drawn down the cold leg shaft 35 to support combustion. In this operation, it is to be understood that the size of the inlet opening to the cold leg or shaft 35 is substantially in proportion to the volume of gas to be burned. The U-passage (35, 17^a, 17, 13, 20^a) acts as an air siphon, the cold air drawn in plus the gas fed to the burner being substantially equal in amount to the gases discharged through the flue; and, since the cold air inlet is proportionate to the volume of gas to be burned, the air thus admitted is substantially only that required for complete combustion of the gas then being discharged by the burner. Due to the siphonic ac-

tion set up, the admission of secondary air depends upon the displacement of gases in the flue, and only when the flue gases are being displaced is cold secondary air drawn in; and, if the gases discharged by the burner were gradually reduced, with a proportionate reduction in displacement of gases in the flueway, there would be a corresponding reduction in the amount of air drawn into the heater. Wherefore, when the main burner is turned off by the temperature control means and only the pilot burner remains burning, the secondary air requirements are reduced to the very minimum and only that minimum requirement of air is supplied. When the pilot alone is operating, the flue products are still heated to some (but a lower) extent, thereby lowering the density of the flue products sufficiently to create an updraft in the flue 20^a; however the temperature of the gases entering the hot leg or flue 20^a is sufficiently low to create only a slight updraft therein, thereby causing but little cold or secondary air to be admitted through the cold leg to the combustion chamber 13. A drag is imposed by the cold leg and, under the foregoing conditions of operation and in furtherance of the siphonic action that takes place, this drag aids in the foregoing result so that the amount of air entering the flue 20^a or hot leg is reduced to near the minimum with a minimized loss of heat on account of transfer of heat from the water surrounding the flue 20 to the flue products.

By way of example, we have found that our purpose may well be served by employing a water heater construction including a storage tank 10 of approximately 28 gallons capacity; a burner 25 having a rated capacity of approximately 27,000 B. t. u.'s located in a combustion chamber approximately 14 inches in diameter and 8 inches in height; a flue 20 of approximately 42 inches and having a cross-sectional area of approximately 7 square inches; and an air shaft 35 approximately 52 inches in length with a cross-sectional area of approximately 5.75 square inches and having an inlet approximately 5.75 square inches in area. In the use of such structure, the standby loss is reduced more than 2 per cent, as a result of which an operating efficiency of at least 8½ per cent more than possible with prior heaters is obtained. It is to be understood that the foregoing structural dimensions are not to be in any sense limiting because they are given merely by way of illustration and, while the dimensions stated are capable of producing excellent results, they may be varied in some or all instances with good results and without departing from our invention.

Our invention is equally well adapted for use with a heater embodying a so-called floater type of storage tank. Such a structural adaptation is illustrated in Fig. 4. The structure there shown includes a cylindrical storage tank 50 surrounded, in spaced relation, at its top and sides by a cylindrical shell or liner 51, which, in turn, is surrounded by another cylindrical shell 52 in spaced relation, providing a space 53 which is filled with a suitable insulation material. The side walls of the shells 51 and 52 extend as at 51^a and 52^a below the bottom 50^a of the tank 50, the inner liner shell 51 being provided with an annular supporting ledge 54 upon which the lower edge of the side wall of the tank seats for support of the tank. The bottom of the tank, together with the downwardly extending walls of the surrounding

shells, forms a combustion chamber 55, the bottom of which is closed by a pan or plate 56 having an opening 57. An imperforate bottom pan 58 carried by legs 59 supports the shells 51 and 52 and, in turn, the tank 50, as in the first-described form.

A burner 60 similar to the burner 25 (Fig. 1) is mounted in the combustion chamber 55, and it may be controlled in a manner similar to the previously described burner structure. The spacing of the shell 50 and liner 51 provides a flueway 61 connected at its lower end with the combustion chamber 55 and at its upper end with an outlet flue section 62 and a draft diverter 63 leading to a stack (not shown).

Air is supplied to the combustion chamber 55 through an air shaft 64 similar to the air shaft 35 (Fig. 1) and located in the insulation between the shells 51 and 52. The outer end of the shaft 64 is connected to atmosphere through a hood 64^a and its inner end is connected to the combustion chamber 55 through a space 65 similar to the space 17^a (Fig. 1). The air shaft 64, space 65, combustion chamber 55 and flueway 61 constitute a continuous U-shaped siphonic passage. One of the main differences between this structure and that of Fig. 1 is that the hot leg or flue of the U-shaped siphon passage takes the form of a flueway passing around the tank wall instead of through it. Overheating of the shaft 64 is avoided by locating it in the insulation in such a way that an insulated space 66 is provided between it and the flueway 61. Obviously, any other suitable means may be employed for preventing or minimizing any tendency to preheat the air flowing through the shaft 64 before it reaches the combustion chamber.

The heater structure shown in Fig. 5 is similar to the structure first described except that it provides an air flow arrangement wherein the gas control devices are located directly in the path of incoming cold air so that they are maintained in a substantially cold condition while, at the same time, providing a heater wherein practically all of the operating parts are completely enclosed, thereby not only enhancing the mechanical utility of the structure but also its appearance.

The structure shown in Fig. 5 is similar to that of Fig. 1 except that a rectangular shaped outer shell 70 surrounds a cylindrical storage tank 71. Also, in this form, the cold leg of the U-shaped siphon passage takes the form, preferably, of a rectangularly shaped air duct section 72 near the upper front portion of the outer shell 70, the shell wall adjacent the same being provided with a plurality of air louvres 73. Beneath the air duct 72, and extending substantially to the bottom of the heater, is another and wider and deeper air duct section 74 connected at its upper end to the lower end of the air duct section 72. The lower end of the air duct section 74 is covered by a plate 75 which also extends throughout the width and depth of the heater shell 70, in which plate are located a plurality of openings 76 connecting the shaft section 74 with a space 77 therebeneath. The space 77 is connected with the combustion chamber 78 by an opening 78 in the plate 75, whereby the cold leg (sections 72 and 74) of the U-shaped siphon passage are connected to the hot leg (flueway 80) by way of the openings 76, the space 77 and the opening 78 in the combustion chamber 79.

A burner 81 similar to the burner 25 (Fig. 1) is located in the combustion chamber 78 and the

flow of gas to this burner is controlled by a thermostatic valve mechanism 82 similar to the thermostatic valve mechanism 30 of the form of Fig. 1. It will be noted that the valve mechanism 82 and its connections are located in the air inlet section 74 directly in the path of the cool air flowing therethrough so that it and its connections are constantly swept by cool air and are thus kept in the desired cool condition notwithstanding the fact that they are located within the heater shell, where they cannot be seen. Access to the valve mechanism is had through a rectangular shaped door 84 which is, preferably, of the friction fitting type similar to the door 42 shown in Figs. 1 and 3. Access to the combustion chamber 79 through the cold air section 74 may be had through an additional friction fit door 85 mounted in the back wall of the section 74 and the side wall of the tank 71 forming a side wall of the combustion chamber 79.

The heater structure shown in Fig. 5 may be mounted in such a way that the combustion chamber 79 is in close proximity to the supporting floor surface, and it may be desirable to provide additional insulating means to prevent any possible overheating of the floor surface. To that end, we may employ a heat baffle plate 86 detachably supported below and shaped similarly to the opening 78. The baffle plate 86 is supported by hanger legs 86a thereon that pass through the opening 78 and engage the upper surface of the plate 75. A deflector plate 87 is supported beneath the baffle 86 by a plurality of brackets 88 carried by the plate 75, as shown, or by the side wall of the shell, or in any other desired manner. The baffle plate 86 and plate 87 are, preferably, formed of metal of any desired kind adapted to serve as a radiant heat deflector, and the advantages thereof will be well understood. We may additionally mount upon the plate 87, directly beneath the combustion chamber, another plate 89 which is shaped to provide, when assembled with the plate 87, a dead air space 90. The use of the plates 86, 87 and 89 entirely avoids the possibility of overheating the floor surface, all without undue restriction in the flow of air from the cold leg of the U-shaped siphon passage to the combustion chamber portion thereof. Other than above described, the construction and operation of this form of device is the same as that shown and described in connection with Fig. 1.

We believe that the operation and advantages of our invention will be readily understood from the foregoing description. The air that must be heated by the burner, as well as the air passing through the flue, is limited to substantially only that required for combustion at all stages of burner operation. This results in a maximum transfer of heat from the flue products to the water and prevents, or at least reduces to the minimum, any tendency for backflow of heat from the water to the flue products during the "off" period of the burner. The added efficiency insured by our invention makes possible a more economical operation, all with the minimum of attention on the part of the user.

It is to be understood that, while we have shown and described three forms of structure embodying our invention and have given one typical dimensional embodiment, other changes in details, arrangements and dimensions of parts may be made without departing from the spirit and scope of our invention as defined by the claims that follow.

We claim:

1. Water heater structure comprising a storage tank, means providing a combustion chamber beneath said tank, means providing a flueway extending upwardly from said combustion chamber lengthwise of said tank, a burner in said combustion chamber, means for supplying fuel to said burner, and means for gravitationally supplying air to said combustion chamber for combustion purposes which includes an air shaft extending substantially parallel with said flueway and externally of said tank and having its upper end connected to atmosphere and the other end connected to said combustion chamber, a shell surrounding said tank and combustion chamber, said shaft being positioned within said shell and spaced from said tank and flueway, said shaft being the only air inlet to said combustion chamber and being so constructed and arranged that the flow of air therethrough is self-induced solely by the normal displacement of the products of combustion in said combustion chamber and flueway.
2. Water heater structure comprising a storage tank, means providing a combustion chamber beneath said tank, means providing a flueway extending upwardly from said combustion chamber lengthwise of said tank, a burner in said combustion chamber, means supplying fuel to said burner, and means for gravitationally supplying air to said combustion chamber for combustion purposes which includes an air shaft extending substantially parallel with said flueway and externally of said tank and being substantially the only air inlet to said combustion chamber, said shaft having an inlet at a height adjacent the exit of said flue, and having an outlet connected directly to said combustion chamber, a shell surrounding said tank and combustion chamber, said shaft being positioned within said shell and spaced from said tank and said flueway, said shaft, combustion chamber and flue constituting a U-shaped or inverted siphonic passage so constructed and arranged that the flow of air therethrough is self-induced solely by the normal displacement of the products of combustion in said combustion chamber and flueway.
3. A water heater which comprises a storage tank, means providing a combustion chamber directly beneath said tank, means providing a flueway extending vertically from said combustion chamber endwise of and beyond said tank, a shell surrounding said tank and combustion chamber and so constructed and arranged that it seals said tank and chamber from the atmosphere, a burner located in said combustion chamber, and means for gravitationally supplying air to said combustion chamber and burner which comprises a vertically disposed air-shaft-forming member mounted between said shell and tank and spaced from said tank and said flueway, means supported by said shell forming an air inlet to said shaft, and conduit means extending horizontally and forming an exit from said shaft leading into said combustion chamber.
4. A water heater which comprises a storage tank, means providing a combustion chamber directly beneath said tank, means providing a flueway leading vertically from said chamber endwise of and beyond said tank, a burner located in said chamber, an outer shell completely enclosing said tank and combustion chamber, and means for supplying air to said chamber which comprises a tubular member forming independ-

ently of and within the confines of said shell a substantially vertical passage leading from a point adjacent the exit of said flueway to the lower part of said shell, means providing an inlet of fixed size to the upper end of said passage, and means providing an exit from the lower end of said passage leading to said combustion chamber, said passage, exit means, chamber and flue providing a continuous, U-shaped passage constituting substantially the only source of air entry and flow through said heater.

5. Water heater structure comprising a water storage tank, means providing a combustion chamber directly beneath said tank, means providing a flueway leading upwardly from said chamber through the water in said tank, a burner in said chamber, a shell surrounding said tank and combustion chamber, means for admitting air to said chamber which includes means inside said shell forming a passage extending substantially parallel with said flueway and externally of said tank and spaced from said tank, and means connecting the upper end of said passage with the atmosphere and its lower end with said chamber, said passage, chamber and flueway being constructed and arranged to provide an inverted, continuous siphonic passage of which said air passage constitutes a cold air leg and substantially the only inlet for air to said combustion chamber, said flueway a hot air leg, and said chamber a connection between said legs.

6. Water heater structure comprising a water storage tank, means providing a combustion chamber beneath said tank, a burner located in said chamber, a shell surrounding said tank and combustion chamber and means for gravitationally controlling the admission of air to said chamber for combustion purposes and controlling the exhaust of burned gases which comprises a U-shaped, inverted siphonic passage including a hot leg in the form of a flueway extending substantially vertically from said chamber lengthwise of said tank, and a cold leg in the form of a passage positioned inside of said shell and spaced from said tank and flueway, said passage extending substantially parallel with said hot leg and having its inlet end terminating at a height near the height of the upper or exit end of said hot leg, and said cold leg having its outlet end connected to said chamber at a point below the inlet to said flue whereby said chamber completes said siphonic passage by connecting said legs, the said U-shaped passage constituting substantially the sole source of air entry and flow through said heater.

7. Water heater structure comprising a storage tank, means providing a closed combustion chamber beneath said tank, a shell surrounding said tank and combustion chamber, a flue member extending upwardly from said combustion chamber longitudinally through said tank in heat transfer contact with the water therein and having an upper exit, a burner in said combustion chamber, means for supplying fuel to said burner, and means by which substantially all of the air for combustion purposes is supplied to said combustion chamber, which means includes an air shaft member extending longitudinally and exteriorly of said tank and providing an air shaft extending substantially the length of said heater structure parallel with said flue member and having its outer end connected to atmosphere near the height of the exit of said flue member and its inner end connected to said combustion chamber at a point below the connection be-

tween the combustion chamber and said flue member, said air shaft member being disposed between said tank and said shell in spaced relation to said tank.

8. Water heater structure comprising a storage tank, an outer shell member surrounding said tank in spaced relation thereto, insulation means disposed in the space between said tank and shell, means providing a closed combustion chamber beneath said tank and disposed inwardly of said insulating means, means providing a flueway leading vertically from said chamber endwise of and beyond said tank, a burner in said combustion chamber, means for supplying fuel to said burner, and means for supplying substantially all of the air to said combustion chamber for combustion purposes, which includes a tubular member surrounded by said insulating means disposed between said tank and shell and providing an air shaft extending substantially throughout the length of the heater structure in substantially parallel relation to said flueway, the upper end of said shaft being connected directly to atmosphere with its lower end connected to the lower portion of said combustion chamber.

9. Water heater structure comprising a water storage tank, means providing a combustion chamber directly beneath said tank, means providing a flueway leading upwardly from said chamber through the water in said tank, a burner in said chamber, a shell surrounding said tank and combustion chamber, and means for admitting air to said chamber which includes members forming a passage extending substantially parallel with said flueway and externally of said tank, said members being positioned inside said shell and spaced from said tank, means connecting the upper end of said passage with the atmosphere at a point adjacent the upper end of said flueway and its lower end with said chamber at a point beneath the latter, said passage, chamber and flueway being constructed and arranged to provide a continuous inverted siphonic passage of which said air passage constitutes a cold leg and substantially the only inlet for air to said combustion chamber, said flueway a hot leg, and said chamber a connection between said legs, said passage inlet having an area proportionate to the area of said flueway and the volume of the gases to be burned by said burner to insure a siphonic action in the siphonic passage.

10. Water heater structure comprising a water storage tank, means providing a combustion chamber beneath said tank, a burner located in said chamber, means for controlling the admission of air to said chamber for combustion purposes and controlling the exhaust of burned gases which comprises a U-shaped, inverted siphonic passage including a hot leg in the form of a flueway extending from said chamber through said tank, and a cold leg in the form of a passage extending substantially parallel with said hot leg and disposed exteriorly of said tank and spaced from the wall thereof, said cold leg having an inlet at its upper end connected to atmosphere near the height of the exit of said flueway and its outlet end connected to said chamber at a point below the connection between the combustion chamber and said flueway whereby said chamber completes said siphonic passage by connecting said legs, a shell surrounding said tank and combustion chamber, said passage having at least a portion within said shell.

11. Water heater structure comprising a storage tank, a first shell member surrounding said

tank and providing with the side wall of the latter a flueway, means providing a closed combustion chamber beneath said tank and with which the inner end of said flue communicates, a second shell surrounding said combustion chamber and said first shell means for supplying fuel to said burner, flue discharge means connected with the outer end of said flueway, and means for supplying to said combustion chamber substantially all of the air used for combustion purposes, which comprises an elongated member located exteriorly of said first shell member and spaced therefrom and extending substantially throughout the length of the heater structure with the outer end of said shaft connected directly to atmosphere and its inner end connected to said combustion chamber below said flueway, said elongated member being positioned inside of said second shell.

12. Water heater structure comprising a storage tank, a shell member surrounding said tank and providing with the side wall of the latter a flueway, means providing a closed combustion chamber beneath said tank and with which the inner end of said flueway communicates, means for supplying fuel to said burner, flue discharge means connected with the outer end of said flueway, means for supplying to said combustion chamber substantially all of the air used for combustion purposes, which comprises an elongated member located exteriorly of said shell member and extending substantially throughout the length of the heater structure with the outer end of said shaft connected directly to atmosphere and its inner end connected to said combustion chamber below said flueway, and another shell member surrounding said first shell member in spaced relation thereto and enclosing said air shaft member, and insulating means disposed in the space between said shell members and between said shell members and said air shaft member.

13. Water heater structure comprising a pair of spaced shell members extending substantially throughout the length of the heater structure, means closing the tops and bottoms of said shell members, insulating means disposed in the space between said shell members, a storage tank mounted within the inner of said shell members in spaced relation thereto and forming with the inner of said shell members a vertically extending flueway around the entire side wall of said tank, said tank having a bottom wall which together with the lower portions of said shell members and said bottom closing means forms a combustion chamber, flue discharge means connected with the upper end of said flue space, a burner located in said combustion chamber, means for supplying fuel to said burner, and means for supplying substantially all of the air to said combustion chamber for combustion purposes, which comprises a member disposed between said shell members and insulated therefrom by said insulating means and extending substantially throughout the length of said shell members, means connecting the outlet end of said shaft directly with the atmosphere, and means for connecting the inner end of said

shaft member with said combustion chamber at a point below said flue space.

14. Water heater structure comprising a storage tank, a first shell member surrounding said tank in spaced relation thereto and forming therewith a flueway, said shell member extending below said tank and forming with the latter a combustion chamber, imperforate means for closing the bottom of the combustion chamber, a vertical air shaft constituting substantially the only inlet for air to said combustion chamber and having its upper end connected to the atmosphere and its lower end to the bottom of said combustion chamber so that said shaft, combustion chamber and flueway constitute an inverted siphonic passage, a second shell member surrounding said first shell member and spaced therefrom to form an insulation chamber, said air shaft being disposed between said first shell member and said second shell member and positioned in said insulation chamber.

15. Water heater structure comprising a storage tank, means providing a combustion chamber directly beneath said tank, a flue leading from said chamber through said tank, a burner in said chamber, an outer shell enclosing said tank and chamber and extending below the latter and adapted to support the heater upon a surface, a bottom member carried by said shell above its lower edge and providing a bottom for said chamber, said member having an opening leading into said chamber, and means for supplying substantially all of the combustion air to said chamber through said opening which includes a member located between said shell and tank and spaced from said tank and providing an air shaft extending from near the top of said tank to said bottom member, said bottom member having one or more openings therein connecting the lower end of said shaft with said opening leading into said chamber.

16. Water heater structure comprising a water storage tank, means providing a combustion chamber beneath said tank, a shell having a closed bottom enclosing said tank and chamber and shutting off the same from the atmosphere, a flue member extending upwardly from said chamber through the water in said tank, a burner in said chamber, and means for supplying substantially all of the air to said chamber for combustion purposes which includes means spaced from said tank and forming a passage between said shell and tank leading from near the top of the latter to near its bottom, the upper part of said passage being connected to the atmosphere and its lower part being connected to said chamber, and means including fuel conduits connected to said burner and adapted to cut in and out said burner according to the temperature of the water in said tank, said latter means being disposed in the lower part of said passage where the same is swept by air incoming for combustion purposes.
